(57) **CLAIM**

The ornamental design for a weight scale apparatus, as shown and described in the Figures.

DESCRIPTION

FIG. 1 is a perspective view of the front, right, and top of the weight scale apparatus in a closed state;

FIG. 2 is a perspective view of the front, left, and bottom of the weight scale apparatus in a closed state;

FIG. 3 is a top plan view of the weight scale apparatus in a closed state;

FIG. 4 is a bottom plan view of the weight scale apparatus in the closed state;

FIG. 5 is a front view of the weight scale apparatus in the closed state;

FIG. 6 is a rear view of the weight scale apparatus in the closed state;

FIG. 7 is a left side view of the weight scale apparatus in the closed state;

FIG. 8 is a right side view of the weight scale apparatus in the closed state;

FIG. 9 is a perspective view of the front, right, and top of the weight scale apparatus in the open state;

FIG. 10 is a perspective view of the front, left, and bottom of the weight scale apparatus in the open state;

FIG. 11 is a top plan view of the weight scale apparatus in the open state;

FIG. 12 is a bottom plan view of the weight scale apparatus in the open state;

FIG. 13 is a front view of the weight scale apparatus in the open state;

FIG. 14 is rear view of the weight scale apparatus in the open state;

FIG. 15 is a left side view of the weight scale apparatus in the open state; and,

FIG. 16 is a right side view of the weight scale apparatus in the open state.
